UNITED STATES PATENT OFFICE.

ROSS R. WEST, OF SAN FRANCISCO, CALIFORNIA.

BANK VAULT.

Application filed November 2, 1925. Serial No. 66,297.

The invention relates to bank vaults and particularly to the provision of a device adapted to be embedded in one wall of the vault, for use as a ventilator, so that, in the event that one of the employees of the bank should be locked in the vault, either accidentally or intentionally, the opening in the wall provided by the device, will permit of sufficient ventilation within the vault to prevent suffocation.

Vaults are constructed to certain rigid specifications, thereby providing a construction which renders the vault substantially immune from successful attack by drills and by the flame of a metal cutting torch.

Vaults are also constructed to preserve the contents against an external rise in temperature, which might be caused, for instance, by the total destruction of the building in which the vault is placed, by fire. In my invention described and claimed in Letters Patent No. 1,549,240, issued to me on August 11, 1925, I provided a ventilating device which, while providing the necessary ventilation, does not render the vault more susceptible of successful attack by drilling or by the torch. The device provided is also heat-resistant to at least the same degree as the walls of the vault, so that heat will not be conducted into the vault through the ventilating device, in the event of the existence of a high temperature exterior to the vault. Briefly described, said ventilating device comprises a metallic sleeve embedded in the wall of the vault, with a closure member therein removable from the interior of the vault, said member being tightly screwed into the sleeve and further locked therein by a screw cap on the inner end of the sleeve. The member and cap were both provided with suitable slots to receive a wrench for unscrewing the same. A suitable wrench for this purpose was provided which was hung or positioned in a convenient location within the vault. It has now been found that this arrangement is not satisfactory, since it is possible for the wrench to become lost or misplaced, with the result that the ventilating device might not be available at the time when needed. Inasmuch as lives are in jeopardy at the time when the need for such a device arises, it is necessary to eliminate every conceivable possibility of failure, and the present invention is in the

nature of an improvement of the ventilating device shown in said Letters Patent, having for its object the provision of such a device with all operable parts connected, thereby eliminating the objectionable features above pointed out.

The invention possesses other advantageous features, some of which with the foregoing, will be set forth at length in the following description, where I shall outline in full that form of the invention which I have selected for illustration in the drawings accompanying and forming part of the present specification. In said drawings I have shown one form of device embodying my invention, but it is to be understood that I do not limit myself to such form, since the invention, as set forth in the claims, may be embodied in a plurality of forms.

Referring to the drawings:

Figure 1 is a section through a device constructed in accordance with my invention and embedded in the masonry wall of a vault.

Figure 2 is a cross section of the device taken on the line 2—2 of Fig. 1.

Figure 3 is a cross section of the device taken on the line 3—3 of Figure 1 and

Figure 4 is an end view showing the combined cap and wrench handle employed for securing and removing the closing plug from the sleeve forming the ventilating passage in the vault.

Vault walls are now usually made of masonry, such as concrete, and I have shown the device of my invention embedded in a concrete vault wall. The device of my invention comprises a metallic sleeve adapted to be embedded in the wall of the vault and provided with means for minimizing the transfer of heat through the metal of the sleeve. For this purpose the sleeve comprises two sleeve parts 4 and 5. The outer sleeve part 4 is preferably provided with an annular exterior flange 6, the outer surface of which is preferably flush with the outer surface of the vault wall. The outer end of the sleeve part 4 is also preferably provided with an inner annular flange 7 having a bevelled inner edge, for reasons that will appear hereinafter. The two sleeve parts are provided at their adjacent ends with outwardly extending annular flanges 12 and 13, between which there is disposed a ring 14 of suitable heat insulating mate-

rial which minimizes the flow of heat longitudinally through the sleeve. The two sleeve parts are secured together by threaded bolts 15, extending through apertures in the flanges 12 and 13. The outer sleeve part 4 is provided on its inner surface, adjacent its inner end, with a screw threaded portion 16, for reasons which will herein-after become apparent. The outer sleeve part 4 is preferably made of a drill resistant steel, so that it will successfully withstand attack. The inner sleeve part 5 is provided on its external surface with a long screw threaded portion 17 and the part 5 is made of sufficient length, so that its inner end projects beyond the inner surface of the vault wall 18. By making the sleeve in two parts, the inner part 5 may be made of a softer steel, so that the inner end thereof may be readily cut off to provide a complete sleeve of any desired length, depending upon the width of the vault wall. The inner sleeve parts 5 are usually made to a standard length, sufficient to fit a vault wall of the maximum thickness and, these sleeves are cut off for vault walls of lesser thickness thereby making it necessary to manufacture only one length of sleeve. The sleeve is held in place on its inner end by a nut 19 engaging the screw threaded portion 17 and bearing against a washer 21 which in turn bears against the vault wall. The sleeve extends beyond the nut 19 for reasons which will subsequently become apparent.

Seated in the sleeve is a removable plug, which may be removed only from within the vault. This plug is formed in two parts, comprising a head portion 22 and a body portion 23. The plug portions are hollow and are provided at their adjacent ends with inturned flanges 24, 25, between which there is arranged a ring 26 of heat insulating material which minimizes the transfer of heat through the plug. The heat insulating ring 26 lies in the same plane as the heat insulating ring 14, so that there cannot be a transmission of heat through the device by the heat passing alternately from the sleeve to the plug and vice versa. The head portion 22 of the plug is provided on its outer surface, adjacent its inner end, with a screw threaded portion which meshes with the screw threaded portion 16 on the sleeve, so that the plug is firmly and rigidly held in place and can be removed only by being rotated. The head of the plug is closed at its outer end by a thick wall 27, which is preferably made of drill resistant steel. At its outer end the head is provided with a projection 28 which fits snugly into the opening in the flange 7, forming a tight contact with the inclined edge 8, so that no crack is left through which material may be introduced into the vault. The hollow interior of the forward portion 22 of the plug is preferably filled with a

material 29 which is torch resisting or drill resisting or both, or with a metal, such as copper.

The flanges 24 and 25 are secured together by a plurality of threaded bolts 30. The inner edge of the flange 24 forms a square opening 31 and the inner edge of flange 25 forms a circular opening 32. A wrench 33 centrally positioned within the body portion 23 extends through the openings 30 and 31. The wrench 33 is square in cross section and adapted to fit the square opening 31 so that the head portion 22 may be screwed in and out of the sleeve portion 4 by rotating the wrench. It is obvious that the opening 31 need not necessarily be square, since any straight sided opening will also serve the same purpose, the wrench of course being shaped to fit the opening. The wrench is preferably locked in the opening 31 by a pin 34 as shown in Fig. 1. By this arrangement, the torque from the wrench is applied directly to the head portion 22, thereby avoiding shearing of the bolts 30 and pin 34. The free end of the wrench 30 extends to an intermediate point within the body portion 23 near its open end and is formed with a flange 35. An extension piece 36, formed with a flange 37 is secured to the wrench 34 by a plurality of bolts 38 which extend through flanges 35 and 37. Preferably a ring 39 of suitable heat insulating material is disposed between the flanges 35 and 37 which further minimizes the flow of heat longitudinally through the sleeve. The wrench extension member 36 extends out of the open end of body portion 23 a suitable distance and is provided at its free end with a hexagonal nut 40 which is keyed thereon as indicated at 41 and secured thereto by a set screw 42.

The inner end of the plug preferably extends beyond the inner end of the sleeve and after the plug has been screwed tightly in place, it is further locked in position by a cap 43, which screws onto the projecting end of the sleeve. The cap 43 also serves as the handle for the wrench 33, and is provided with a central opening 44 through which the wrench extension 36 projects. The central opening 44 is counter-bored and shaped to fit the nut 40 as indicated at 45, and on its periphery, the cap is provided with a plurality of handles 46 for rotating the same. The cap 43 is slipped over the end of the extension piece 36 after which the nut 40 is secured to said piece as described. When placing the plug in the sleeve, the cap is moved rearwardly to engage the nut 40 and rotated until the plug is screwed into the sleeve, after which the cap is slipped forward and itself tightly screwed on the sleeve. For removing the plug from the sleeve, the reverse operation takes place. Preferably, the nut 19 may be

provided with a switch mechanism of an alarm system, which may be of any standard type and indicated at 47, which is actuated by a plunger 48. The plunger 48 ex-

a wrench in engagement with said means and projecting from the inner ends of said sleeve and plug and means on the projecting end of said wrench for rotating the same.

5 tends through the wall of inner part 5 and engages the outer surface of the body portion 23, which is provided with a peripheral slot 24, as shown in Fig. 3. This slot is so positioned with respect to the plunger 48 10 that when the plug is rotated for removal from the sleeve, the plunger may drop into the same and actuate the alarm mechanism, thereby indicating that the ventilating passage is being opened by someone in the

70 vault.

5. The combination with a vault wall, of a metallic sleeve embedded in and extending through said wall, a plug having a hollow body and a drill resistant head screwed into said sleeve, a socket within said head, a wrench in engagement with said socket positioned within the hollow body and projecting therefrom and means on the projecting end of said wrench for rotating the same.

10 15 From the foregoing, it will be seen that I have provided an improved ventilating device, combining the desirable features above pointed out, in which all of the operating parts are connected, thereby preventing loss or misplacement of parts, and which is simple and readily operable and available at all times.

I claim:

25 1. The combination with a vault wall of a metallic sleeve embedded in and extending through the wall, an annular shoulder on the inner side of the sleeve at its outer end, a plug screwed into said sleeve and forming 30 a tight engagement with said shoulder, and means for rotating said plug comprising a wrench positioned within the plug and extending therefrom and means for rotating said wrench.

6. The combination with a vault wall, of a metallic sleeve embedded in and extending through the wall, said sleeve being provided on its inner end with a screw threaded portion and being provided on its inner surface with a screw threaded portion, a plug 35 engaging the latter screw threaded portion and closing the aperture through the sleeve, a cap engaging the former screw threaded portion and overlying the inner end of the plug and means for rotating said plug comprising a wrench in engagement with said plug and extending through said cap.

35 2. The combination with a vault wall of a metallic sleeve embedded in and extending through the wall, an annular shoulder on the inner side of the sleeve at its outer end, a plug screwed into said sleeve and forming a tight engagement with said shoulder, and means for rotating said plug comprising a wrench positioned within the plug and secured thereto at one end, the opposite end extending from the inner ends of 40 the plug and sleeve and having means for rotating the same.

7. The combination with a vault wall, of a metallic sleeve embedded in and extending through the wall, said sleeve being provided on its inner end with a screw threaded portion and being provided on its inner surface with a screw threaded portion, a plug 45 engaging the latter screw threaded portion and closing the aperture through the sleeve, a cap engaging the former screw threaded portion and overlying the inner end of the plug, said cap having a central opening and a socket on its exterior surface surrounding said opening, and means for rotating said plug comprising a wrench in engagement with said plug and projecting through said cap central opening, and a nut fixed on the projecting end of said wrench adapted to fit the socket in said cap.

50 3. The combination with a vault wall, of a hollow metallic sleeve embedded in the wall and extending therethrough, a hollow plug screwed into said sleeve having an inner transverse wall at an intermediate point formed with a straight-sided opening, a wrench in engagement with said opening and projecting from the inner ends of the 55 sleeve and plug and means on the projecting portion of said wrench for rotating the same.

8. The combination with a vault wall, of a metallic sleeve embedded in and extending through the wall, said sleeve being provided on its inner end with a screw threaded portion and being provided on its inner surface with a screw threaded portion, a plug 60 engaging the latter screw threaded portion and closing the aperture through the sleeve, a cap engaging the former screw threaded portion and overlying the inner end of the plug, said cap having a central opening and a socket on its exterior surface surrounding said opening, and means for rotating said plug comprising a wrench in engagement with said plug and projecting through said cap central opening, and a nut fixed on the projecting end of said wrench adapted to fit the socket in said cap and means on the

9. The combination with a vault wall, of a metallic sleeve embedded in and extending through the wall, said sleeve being provided on its inner end with a screw threaded portion and being provided on its inner surface with a screw threaded portion, a plug engaging the latter screw threaded portion and closing the aperture through the sleeve and means for rotating the plug comprising a wrench in engagement with said plug and projecting from the inner end of said sleeve, a nut on the projecting end of said wrench and a cap slidable on said projecting wrench end having threads for engaging the former screw threaded portion in one position and a socket for receiving said nut in another position.

10. The combination with a vault wall, of a metallic sleeve embedded in and extending through the wall, said sleeve being provided on its inner end with a screw threaded portion and being provided on its inner surface with a screw threaded portion, a plug engaging the latter screw threaded portion and closing the aperture through the sleeve and means for rotating the plug comprising a wrench in engagement with said plug and projecting from the inner end of said sleeve, a nut on the projecting end of said wrench and a cap slidable on said projecting wrench end having threads for engaging the former screw threaded portion in one position and a socket for receiving said nut in another position.

15. The combination with a vault wall, of a metallic sleeve embedded in and extending through the wall, said sleeve being provided on its inner end with a screw threaded portion and being provided on its inner surface with a screw threaded portion, a plug engaging the latter screw threaded portion and closing the aperture through the sleeve and means for rotating the plug comprising a wrench in engagement with said plug and projecting from the inner end of said sleeve, a nut on the projecting end of said wrench and a cap slidable on said projecting wrench end having threads for engaging the former screw threaded portion in one position and a socket for receiving said nut in another position, and means on the periphery of said cap for rotating the same.

20. The combination with a vault wall, of a metallic sleeve embedded in and extending through the wall, said sleeve being provided on its inner end with a screw threaded portion and being provided on its inner surface with a screw threaded portion, a plug engaging the latter screw threaded portion and closing the aperture through the sleeve and means for rotating the plug comprising a wrench in engagement with said plug and projecting from the inner end of said sleeve, a nut on the projecting end of said wrench and a cap slidable on said projecting wrench end having threads for engaging the former screw threaded portion in one position and a socket for receiving said nut in another position, and means on the periphery of said cap for rotating the same.

In testimony whereof, I have hereunto set my hand.

ROSS R. WEST.
